WOOD ELLIOTT FISHER COMPANY, OF NEW YORK, N. Y., A CORPORATION OF DELA-
WARE

TYPEWRITING MACHINE

Application filed February 29, 1932. Serial No. 595,801.

This invention relates to typewriting machines, and particularly to platen-feed-roll mechanism therefor.

In typewriting machines or the like, there are usually provided, tangent to the platen, two parallel lines of feed-rolls connected together to move in unison into and out of engagement with the platen or with a work-sheet around the platen. In the form of feed-roll mechanism to which the present invention is applicable, each line of feed-rolls includes a supporting shaft along which said rolls are spaced at suitable intervals for free rotation on said shaft. Spacers are used to separate the individual rolls on each shaft, and great care has been necessary heretofore to have the feed-rolls and spacers of precise length, so that there might be neither binding of the rolls nor excessive end play there-
of. Binding would prevent free rotation of the rolls on the shaft, and excessive end play would cause the work-sheets to slip sidewise or skew when the platen-carriage was suddenly arrested during carriage return or tabulating movements. Heretofore tubular spacers have been employed for spacing and separating the feed-rolls along their supporting shaft, the whole line of rolls thus assembled being retained against axial displacement by suitable abutments formed at the ends or provided as part of the shaft supports at intermediate portions of the shaft. Such abutments fix a considerable length of shaft within which a plurality of individual feed-rolls and spacers must be retained without end play. Even very small variations in the lengths of the several feed-rolls and spacers strung out between the abutments are liable to become cumulative.
In assembling a line of feed-rolls and spacers, it was necessary to either select a group of rolls and spacers whose combined length was just right, to choose a group whose combined length was a little too long, and then reduce the length of one or more members, or to have one spacer or feed-roll of sufficiently excess length that it might be reduced to effect a proper length of any group. Such procedure was not only troublesome and ex-

pensive, but was a bar to easy interchangeability of the parts.

Narrow tubular collars settable along the shaft have also been used heretofore to eliminate feed-roll side play. In some cases, these collars were secured to the shaft by means of screws. It was found, however, that a collar would sometimes, through loosening of the screw, become displaced endwise along the shaft, with a corresponding increased end play of the feed-roll. In other cases, these narrower collars were retained in place upon the shaft by means of a forced fit upon said shaft. Such forcing of the collar along the shaft would often score the latter, the scoring of the shaft retarding or preventing the rotation of the rolls. The tight-fitting collars also rendered it impracticable to replace a worn-out or damaged feed-roll.

The present invention aims to use feed-rolls whose lengths may vary within the limits of easily maintained manufacturing tolerances, and to compensate for such variation by providing spacers of adjustable lengths.

The invention further aims to provide such a spacer in a form which may be economically made and applied, and which shall efficiently serve its purpose. To these ends, the invention provides a spacer whose two ends are annular collars or rings spaced apart, but connected by strips joined at their ends to said collars or rings, and which strips may be bent to extend or contract the length of the resulting spacer. For changing the spacer-length in the simplest and most effective manner, each strip is joined at its ends to the collars or rings at points which lie in a line extending in a helical or biased direction around the shaft-axis. The strips themselves may be of a shape substantially conforming to this line. It results from this helical form or biased connection of the connecting strip or strips that a torsional twist given to one end of the spacer relatively to the other end causes the strip-portion to be extended or contracted lengthwise of the spaces or shaft-axis with a corresponding lengthening or shortening of the whole spacer.

For producing the spacers economically,

- they may be stamped out of flat stock, and then rolled into a sleeve, easily slipped on the shaft. The blank or stamping would include two parallel strips spaced apart, but joined by 5 diagonal strips, the first-mentioned strips forming collars or ends of the spacer when the blank is rolled and formed into a sleeve, the diagonal strips of the blank forming the biased connecting strips or links between said 10 collars. The number of biased strips joining the end collars of each spacer may be only one, or there might be more than the two diametrically opposite strips shown in the illustrated form of the invention.
- 15 The use of the novel spacers affords ready interchangeability of the parts. Furthermore, any feed-roll may, if necessary, be easily removed or replaced.
- 20 The spacers, loosely mounted on the feed-roll shafts, are placed between the feed-rolls. Suitable means, as, for example, the heads of holding screws threaded into the ends of the shafts, are provided to retain the whole line of rolls and spacers on the shaft. The shaft 25 with the feed-rolls and spacers is then mounted in the machine, and the rolls are tested for side play and free rotation. If any side play is found, one or more of the spacers is lengthened until all side play is eliminated. Should 30 it be found that any of the feed-rolls is binding against the spacers, one or more of the latter is shortened just enough to enable the rolls to revolve freely without introducing any side play.
- 35 When it is desired to replace worn-out or damaged feed-rolls in the machine, the shaft carrying the set of rolls and spacers is lifted out of the machine, and one of the end holding screws is removed, when any or all of the 40 feed-rolls and spacers are free to slide off of the shaft, and the necessary replacements may be made. The parts are then reassembled, replaced in the machine and the spacers readjusted.
- 45 Suitable pliers or other collar gripping tools may be applied to the collars forming the ends of the spacer, which collars may thereby then be twisted, one relatively to the other, to lengthen or shorten the spacer.
- 50 Other features and advantages will herein-after appear.

In the accompanying drawing,

Figure 1 is a perspective view, showing a portion of a typewriter platen and carriage and two lines of feed-rolls with the improved spacers applied as separators for said feed-rolls.

Figure 2 is a top plan view of the feed-roll assembly, and brings out details of the 60 application of the novel spacers, not apparent in Figure 1.

Figure 3 is a perspective view, indicating how pliers or other suitable tools may be applied to the ends of the novel spacer to give 65 a torsional twist to one end relatively to the

other end, for lengthening or shortening the spacer.

Figure 4 is a perspective view, showing the novel spacer alone, and also showing how it has been rolled into sleeve form from a flat blank.

Figure 5 is a plan view, showing the form of the spacer-blank.

The usual platen 10 is fixed on a platen-shaft 11 journaled in end plates 12 of a platen-frame 13 that includes a tie-rod or shaft 14 and a paper-table 15. The paper-table extends down at the rear of the platen and curves beneath the same to form a deflector 16 for guiding the paper down at the rear of the machine, around the bottom of the platen and up toward the printing point.

The platen may be rotated by the usual line-spacing mechanism (not shown) or by the usual end knobs 17 fixed to the platen-shaft.

Extending along and pressing against the lower part of the platen are sets of individual feed-rolls 18 and 19, rotatable on shafts 20 and 21, respectively. Each shaft rests in hooked portions 22 of arms 23 swingable on the tie-rod 14 and held pressed towards the platen by springs 24. These arms are positioned on the tie-rod 14 to support each feed-roll shaft near its end portion and are retained laterally without side play by collars 25 fastened to the rod 14.

The feed-rolls are normally held pressed against the platen by the springs 24, but may be released by operating the usual release lever (not shown) to raise a link 26 and rock a shaft 27 having flat portions 28 which abut extensions 29 of the arms 23. The rocking of the shaft 27, effected by raising the link 26, swings the extensions 29 outwardly from the shaft 27 to rotate the arms 23 away from the platen and cause all of the feed-rolls to become released from the platen. Subsequent restoration of the link 26 and shaft 27 causes the feed-rolls to reengage the platen.

The larger or rear set of feed-rolls are formed of a soft rubber tubing 30 fixed to an inner metal tubing 31 having metal bushings 32 rigidly connected in the ends of the metal tubing by a forced fit.

This construction minimizes the weight of larger rolls 18 and also makes said weight more equal to that of the smaller front rolls 19 which are formed of a rubber tubing 33 fixed over a metal tubing 34. These rolls are slipped onto the supporting shafts for free rotation thereon and are spaced apart to occupy different positions along the platen. Although the feed-rolls must be freely rotatable on the shaft, it is essential that the slightest endwise movement of the feed-rolls be eliminated. For this purpose adjustable sleeves or spacers 35 are placed on the shafts 20, 21, in the spaces which separate the rolls 18 or 19. The adjustable spacer is made by

bending a flat stamped-out piece of stock (Figure 5), to form a pair of circular collars 36 (Figure 4), connected and held apart by a pair of strips 37 joined at their ends to 5 said collars.

As seen in Figure 5, the spacer punching or blank includes a pair of parallel strips 36 of equal lengths that make up the collars 36, Figure 4, when said blank is rolled or otherwise shaped into the sleeve-form shown in 10 said Figure 4. Figure 5 further shows how the parallel collar-strips 36 are spaced apart and connected by the pair of parallel strips 37 inclined to the collar-strips 36, each connecting strip extending diagonally from one 15 of the ends of a collar-strip 36 to an inner portion of the opposite collar-strip 36. When the blank, Figure 5, is rolled or otherwise shaped to form the sleeve shown in Figure 20 4, the connecting strips assume a helical curvature and space the collars 36 apart to fix a nominal overall length of the spacer thus formed. Spacers of different lengths 25 may be provided by making different blanks wherein the lengths of the connecting strips 37 vary according to the spacer-length desired.

For spacers of the length indicated in the drawing, the points where the ends of each 30 strip 37 join the collars 36 may be spaced about one-quarter turn apart circumferentially of the spacer. For shorter spacers, this circumferential spacing may be decreased, and for longer spacers such circumferential spacing may be increased. The 35 spacer herein illustrated, Figure 4, employs two strips 37 diametrically opposite one from the other, so that the end faces of the spacers may remain substantially in parallelism irrespective of the twist given to the end 40 collars 36 for adjusting the spacer-length.

As shown in Figure 3, a spacer may be gripped circumferentially at its end collars 36 by two pliers 48. By turning said pliers 45 in the direction indicated by the arrows, and at the same time, of course, gripping the collars 36, the spacer is twisted from the form indicated by the broken line 49, which represents the connecting strip 37 to the form 50 indicated by the full line representing said connecting strip 37. During this twisting, the overall length of the spacer will have been extended by an amount indicated by the 55 separation of the broken line 50, representing the collar 36, from the full line representing said collar. Conversely, it will be evident that a twist given to the end collars, relatively to one another in a direction opposite to that indicated by the arrows, in 60 Figure 2, will shorten the overall length of the spacer.

The feed-rolls 18, 19 and spacers 35 are retained on their respective shafts 20, 21 by screws 38 threaded into and tightened 65 against the ends of the shafts, so that the

screwheads, larger in diameter than the shafts, form abutments for the end feed-rolls. The inner feed-rolls 18 of the rear shaft 20 are separated and spaced endwise by the spacers 35. Said shaft 20 has portions 70 39 that are reduced in diameter adjacent the inner side of the end feed-rolls, and these portions 39 have diameters fitting the hooks 22 of the arms 23.

Endwise of the shaft, the portions 39 75 (Figure 2) are wider than the arms 23, so that said arms 23 may be adjusted by bending laterally to eliminate any side play of the end feed-rolls, or to free said rolls which are located between the holding screws 38 80 and said arms 23. Any side play of the center rolls may now be eliminated by twisting the collars 36 of a spacer 35 in opposite directions, as aforesaid, for lengthening a 85 spacer. When a shaft is first assembled, the amount of said play may be large, due to the inaccuracies of manufacture, so that it becomes expedient to lengthen all the spacers to eliminate all of the side play of the rolls 18, leaving only sufficient clearance for the 90 free rotation of the rolls. It will be understood that a spacer may also be shortened by twisting the end collars in proper direction, as aforesaid, said shortening being done when a feed-roll binds and is to be freed.

The front feed-roll shaft 21 also supports a set of narrow annular soft rubber pads 40 mounted in grooved bushings 41. These pads engage the deflector 16 adjacent the 100 openings 42, which clear the front feed-rolls and hold the deflector in close proximity to the platen when the feed-rolls are in their paper-feeding position. A feed-roll 19 and a bushing mounted pad 40 are located end to end at each end portion of the front feed-roll shaft 21, and are retained between an arm 23 and an abutment screw 38. These arms 23 are also bent to eliminate any side play of the end feed-rolls, or to free said rolls without introducing side play. The 105 side play between the center feed-rolls 19 is eliminated, or said rolls are freed, by adjustment of a spacer 35 located between an arm 23 and a center roll 19. If desired, a plain non-adjustable spacer in the form of a tubing 43 may be placed between the center rolls since the two adjustable spacers on the shaft are sufficient to eliminate all end play of the center rolls, or to free said rolls.

Variations may be resorted to within the scope of the invention, and portions of the improvements may be used without others.

Having thus described my invention, I claim:

1. The combination with a feed-roll shaft and a plurality of feed-rolls spaced at intervals along said shaft, of means for spacing said rolls and securing them against displacement lengthwise of said shaft, said means including an elongate spacing sleeve 120

- whose ends are collars surrounding said shaft, said sleeve including a strip joined to and spacing said collars apart, said strip being formed so as to be bendable for changing the spacing between said collars, and thereby adjusting the over-all length of the sleeve.
2. In a feed-roll assembly, the combination with a feed-roll shaft and a feed-roll 10 rotatable on said shaft, of means abutting one end of said feed-roll, a member of said assembly spaced lengthwise of the shaft from the other end of said feed-roll, and an elongate spacer of adjustable length on said shaft, having one end abut said other end of said feed-roll and having the other end abut said member, said length being adjustable to adjust end play of said feed-roll.
3. An adjustable spacer formed of two end 20 collars and a strip or strips joined to and connecting said end collars, said strip or strips being bendable to contract or expand the distance between said collars, and thereby vary the length of the spacer.
4. Adjustable means for spacing rolls and securing them against lengthwise displacement, said means including an elongate spacing sleeve whose ends are collars, said sleeve including connections spacing said collars apart and joined thereto at points biasing 30 said connections circumferentially of the sleeve, whereby twisting one end or collar of the sleeve relatively to the other end or collar changes the length of the sleeve.
5. An adjustable spacer formed of two end collars, and including diametrically opposite helical strips, each strip having its ends joined to and thereby connecting and spacing said end collars, said spacer being capable of having its length shortened or extended by twisting one end collar relatively to the other, and by virtue of the resulting winding or unwinding of said helical strips.
6. In a machine having a shaft and feed- 40 rolls spaced along said shaft, a feed-roll spacer formed of a sheet-metal blank having parallel spaced-apart end strips and diagonal connecting strips, said blank being rolled or otherwise shaped into a sleeve which may be slipped onto said shaft, so that the first- 50 mentioned parallel strips form end collars and the diagonal strips form helical connecting strips between said collars, the length of said sleeve being adjustable by twisting one collar relatively to the other, thereby winding or unwinding the helical strips, said end strips being of lengths which result in the ends of said strips abutting to form collars that are complete circumferentially when the blank is shaped into a sleeve.
7. In a machine having a shaft and feed- 60 rolls spaced along said shaft, a feed-roll spacer formed of a sheet-metal blank having parallel spaced-apart end strips and diagonal connecting strips, said blank being rolled or otherwise shaped into a sleeve which may be slipped onto said shaft, so that the first-

- mentioned parallel strips form end collars and the diagonal strips form helical connecting strips between said collars, the length of said sleeve being adjustable by twisting one collar relatively to the other, thereby winding or unwinding the helical strips, said end strips being of lengths which result in the ends of said strips abutting to form collars that are complete circumferentially when the blank is shaped into a sleeve.
8. A spacer formed of a sheet-metal blank having parallel spaced-apart end strips and diagonal connecting strips, said blank being rolled or otherwise shaped into a sleeve, so that the first-mentioned parallel strips form end collars and the diagonal strips form helical connecting strips between said collars, the length of said sleeve being adjustable by twisting one collar relatively to the other, thereby winding or unwinding the helical strips, said diagonally strips being disposed in said blank so that the helical strips into which said diagonal strips are transformed when the blank is shaped into the sleeve are evenly spaced circumferentially of said sleeve.
9. A spacer formed of a sheet-metal blank having parallel spaced-apart end strips and diagonal connecting strips, said blank being rolled or otherwise shaped into a sleeve, so that the first-mentioned parallel strips form end collars and the diagonal strips form helical connecting strips between said collars, the length of said sleeve being adjustable by twisting one collar relatively to the other, thereby winding or unwinding the helical strips, said end strips being of lengths which result in the ends of said strip abutting to form collars that are complete circumferentially when the blank is shaped into a sleeve, said diagonal strips being disposed in said blank so that the helical strips into which said diagonal strips are transformed when the blank is shaped into the sleeve are evenly spaced circumferentially of said sleeve.
10. In a typewriting machine or the like having a revoluble platen, feed-roll mechanism including a shaft parallel to said platen, a plurality of feed-rolls for co-operating with said platen and spaced along said shaft from end to end, transverse arms supporting said shaft and swingably mounted for effecting movement of said rolls to and from the platen, the ends of said shaft having feed-roll abutments, and the arms being spaced from said abutments and from one another, and spacers of adjustable lengths co-operating with said arms and abutments to space the feed-rolls along said shaft, the spacers having provision for adjusting their lengths, and the arms being adjustable lengthwise of the shaft, to take up end play of all the feed-rolls or to free said rolls without introducing end play in any of them.
11. In a typewriting machine or the like having a revoluble platen, feed-roll mecha-

nism including a shaft parallel to said platen, a plurality of feed-rolls for co-operating with said platen and spaced along said shaft from end to end, transverse arms supporting said shaft and swingably mounted for effecting movement of said rolls to and from the platen, the ends of said shaft having feed-roll abutments, and the arms being spaced from said abutments and from one another, and spacers of adjustable lengths cooperating with said arms and abutments to space the feed-rolls along said shaft, the spacers having provision for adjusting their lengths, and the arms being adjustable lengthwise of the shaft, said spacers being formed of end collars and biased links joined to and connecting said collars, whereby, when one end collar is twisted relatively to the other, the overall length of the spacer is lengthened or shortened, adjustment of said arms and spacers, as aforesaid, being effective to take up end play of all the feed-rolls or to free said rolls without introducing end play in any of them.

WILLIAM F. HELMOND.
